[57] CLAIM

The ornamental design for a sailboat, as shown and described.

DESCRIPTION

FIG. 1 is a perspective view of a sailboat showing our new design;

FIG. 2 is a side elevational view thereof, the opposite side being a mirror image of that shown;

FIG. 3 is a rear elevational view thereof;

FIG. 4 is a front elevational view thereof;

FIG. 5 is a top plan view thereof;

FIG. 6 is a bottom plan view thereof.

The broken line illustration of a mast and sail shown in FIGS. 1 and 2, and a mast shown in FIGS. 3 and 4 is for illustrative purposes only and forms no part of the claimed design.
